UNITED STATES PATENT OFFICE.

JOHN T. McGARRY, OF CINCINNATI, OHIO.

SWITCH-INTERLOCKING DEVICE.

Application filed October 19, 1925. Serial No. 63,403.

My invention relates to switches and switch-stands and interlocking devices therefor, wherein there is provision for insuring that the point rail of the switch has been drawn safely close to the stock rail, through the medium of a retentively engaging means or plunger coating with an interlocking bar connected to the point rail.

An object of my invention is to reduce as far as possible the chance of the interlocking mechanism being disrupted by any object dragged or thrown alongside the switch, such as an object projecting from a passing train, or such as some object struck by a train, as a vehicle, being thrown thereby alongside the switch. A further object is to provide for padlocking the interlocking device in such a manner that the lock will be fully protected in such accidents as just instanced, so that the switch not only is held closed, against the effects of vibration of the passing trains, after such an accident resulting in destruction of the switch-stand, but also is kept safely locked, pending repair of the switch-stand; and in fact using the device as means for locking the switch against tampering and the like, instead of the padlock as usually applied, directly to the switch-stand and subject to being carried away with the stand in such accidents. A further object is to make the operating mechanism of the device as simple and reliable as possible, guarding also against the device becoming inoperative from wear or loosening of any part of the mechanism, or from clogging by dirt or ice. A further object is to minimize the obstruction offered by the device, when installed alongside the switch-stand, to the switchman approaching the stand to operate it, and to make the device itself most convenient for the switchman to operate for disengaging the interlocking means preparatory to throwing the switch. Other objects will appear in the course of the ensuing description.

I attain these objects by the device illustrated, for example, in the accompanying drawings, in which—

Figure 1 is a general perspective view of part of a switch and a switch-stand connected thereto and having my improved interlocking device applied thereto;

Fig. 2 is a rear end elevation of the device and part of the head block in which it

is mounted, part only of the interlocking bar being shown, and the casing therefor being omitted;

Fig. 3 is a vertical cross-section of the interlocking bar and its casing and part of the head block, to which the latter is attached;

Fig. 4 is a similar view showing the interlocking bar and its casing as used in the modification of my invention illustrated in Figs. 7, 8 and 9;

Fig. 5 is a plan view corresponding to Fig. 2, part of the base of the switch-stand being shown.

Fig. 6 is a vertical longitudinal section on the plane of the line 6—6 of Fig. 5;

Fig. 7 is a plan view similar to Fig. 5, showing the modification of my invention;

Fig. 8 is a sectional view, similar to Fig. 6, further illustrating the modification; and

Fig. 9 is a partial rear end elevation of this modification.

As exemplified in Figs. 1 to 6, inclusive, the interlocking bar 1 has the round threaded end 2 extending through the bent-down end of a plate 3 which, as is known in the art, is fixed to the end of the point rail 4 of the switch; and nuts 5 and 6 are screwed onto this end part 2 against opposite sides of the plate 3, so that this bar 1 is very intimately connected to the thin end part of the point rail 4. It will be understood that my improved device may be used in conjunction with any type of switch-stand desired; the stand shown herein (Fig. 1) being that well known kind with a high frame 7 in which a shaft 8 is journaled vertically, carrying on its lower end the crank 9 which is connected to the two point rails 4 and 10 by the rods 11 and 12 in the usual manner. At the top of the frame 7 a hand lever 13, fixed on the shaft 8, swings around a segment 14 ninety degrees to throw the switch, and is jointed so that its outer end part may drop into either one of two notches 15 and 16 in the segment, where it may be locked against withdrawal by inserting a padlock in an ear 17 at the joint of the lever. This padlock is not shown; as I prefer to lock the switch by means of a padlock applied directly to the interlocking device, as will be described.

The interlocking bar 1 extends alongside the adjacent head block 18 of the switch,

some distance below the top thereof, being, for most of its length, of rectangular cross-section, and, in this example, having its broader sides horizontal. The interlocking housing 19, in the present example, comprises a top 20 fastened down on the top of the head block 18 just beyond the switch-stand from the track, by means of four screws 21, and extending across and partly covering a gain 22 cut entirely across the head-block 18 and somewhat less than half way down therethrough. This housing also comprises the stirrup 23 having the transverse rectangular opening 24 through which the outer end part of the interlocking bar 1 slides in its movement with the switch rail 4; this stirrup 23 having wing portions 25 through which, preferably, two additional screws 26 are passed below the bar 1 into the side of the head block 18. Above the stirrup 23 and forming its junction with the top 20, is the head 27, in which is a cavity 28 registering with the adjacent end of the gain 22; and a bore 29 extends up through the bottom of the stirrup, with an alined continuation 30 in the top of the stirrup, into the cavity 28, so that the plunger 31, with its top eye 32 in the cavity 28, may slide up and down in these bores 29 and 30, across the interlocking bar opening 24. The interlocking bar 1 has the opening 33 down through it, so located that, when the bar 1 is properly adjusted by means of the nuts 5 and 6 at the point rail, this bar opening 33 will register with the bores 29 and 30 of the stirrup, and the plunger 31 can pass down through the bar 1, if the point rail 4 is drawn snugly to the stock rail 34, in its correct safe relation thereto, but not otherwise.

Preferably, the eye 32 of the plunger 31 is wider than the bore 30, so that the plunger 31 cannot drop down therethrough, even though it were detached from its operating mechanism. This operating mechanism comprises the lever 35 having a fork 36 straddling the plunger eye 32, with a pin 37 transversely through the fork members and the eye; and preferably the sides of the cavity 28 are close enough to prevent escape of this pin 37 endwise. Intermediate of its ends the lever 35 has a hub 38 with a transverse bore; and the top 20 of the housing 19 has a wall depending into the gain 22 of the head block, this wall comprising side parts 39 with transverse bores, receiving the lever hub 38 between them and having the fulcrum pin 40 passed through the alined bores and firmly fastened at its ends at the outer sides of the wall parts 39. Preferably, the wall also comprises a lower part 41 adjoining the side parts 39 below the hub 38 and fitting rather closely to the bottom of the head block gain 22, as do the side parts 39 to the sides of the gain; so that this wall, with the lever hub 38 in it, makes up a sub-

stantial closure of the part of the gain 22 next to the head cavity 28, in which the forward arm of the lever 35 swings up and down.

The opposite arm of the lever 35 swings up between two ledges 42 formed by curving the housing top 20 downward over the edges of the gain 22 and then inward partly thereacross, from the fulcrum wall to the end of the top; these ledges also joining said wall above the hub opening thereof. On the top of this outer arm of the lever 35 is the locking ear 43, the transverse opening 44 of which is above the ledges 42 when the plunger 31 is down in the interlocking bar 1; so that if the bow of a padlock 45 (Fig. 1) is passed through the opening 44 it prevents depression of this outer end of the lever 35, and raising of the plunger 31, by engagement with the side ledges 42 of the housing. Preferably, ribs 46 extend from the respective ledges 42 down and forward to the wall side portions 39, and other ribs 47 extend from these wall portions 39 forward to the respective sides of the head 27; all these ribs 46 and 47 fitting rather snugly to the sides of the gain 22. Thus the ribs reinforce the connection of the top 20 and head 27, and by engagement with the sides of the gain reinforce the fixing of the housing 19 to the head block 18 by the screws 21 and 26. On the rear end of the lever 35, as here illustrated, is formed the treadle 48, within the end part of the gain 22 and swinging close to the rear ends of the ledges 42. When the treadle end of the lever is depressed, raising the plunger 31 out of the interlocking bar 1, so that the switch may be thrown, the ear opening 44 is below the ledges 42, which, together with the treadle 48 immediately to the rear of, and now slightly below, the ledges 42, prevents insertion of the padlock 45. Thus it is impossible to padlock the device unless the plunger 31 is engaged fully through the interlocking bar; and it has been seen that this engagement cannot occur unless the point rail 3 is in safe relation to the stock rail 34.

To afford ample space for insertion of the switchman's foot to the treadle 48, the gain 22 is widened from its front end adjoining the head cavity 28, to its rear end containing the treadle; this widening being increased in its upper region, to the rear of the housing top 20, by beveling the corners 120 of the gain, at 49, preferably. Also, preferably, to afford better drainage from the mechanism, the gain 22 is deepened from front to rear, so that entrance of water or snow to the interior of the device, or retention thereof, is hindered. The widening and deepening of the gain also facilitates sweeping such substances therefrom.

The front end or head 27 is made convex, with curves of ample radius, exteriorly, and

it preferably has its top carried somewhat above the upper surface of the main housing top 20 as shown, acting as a fender for the heads of the screws 21, with relation to objects thrown or dragged forcibly over the device, in accidents such as hereinbefore alluded to, if coming toward the front of the installation. The locking means and the treadle being down behind this raised head 27 and top 20, these are protected in a much better manner than they are in switch devices having the locking and operating means substantially above the top of the head block. Against collision of objects coming from the opposite direction, the other head block 18^a offers considerable protection, as also does the switch-stand structure, which might be disrupted but would tend to divert the colliding object up and over the interlocking device. Also, the most danger is present from such collisions in switch-facing direction; as a freeing of the point rails makes derailment certain, whereas such an accident with the train running in opposite direction would still permit the wheel flanges to overcome the rail displacements. Also, in the cases of vehicles being thrown by trains against the switch-stands, at road crossings, the switches almost always face the crossings, so that the collision is in facing direction. It is for these reasons that I present the more effective guards in opposition to approach in switch-facing direction, as disclosed.

In conformity with this plan, I also provide a guard or casing 50 over and around that part of the interlocking bar 1 between the stock rail 34 and the housing 19, and also, preferably, an additional or terminal guard section or casing 51 over and around the end part of the bar 1 out past the housing 19 (Fig. 1.) It will be seen that this interlocking bar 1 is effectively guarded against collisions coming in the opposite direction, by the head block 18 itself; but as these bars ordinarily have been used, they are entirely exposed to collision coming in switch-facing direction, which it is the object of my guards or casings to counteract. The casing 50 is approximately channel shaped, turned on its side or partly inverted; the upper side 52 being the deeper and overlapping the adjacent top surface of the head block 18, to which it is fastened by screws 53 at intervals therealong. What would be the bottom of the channel thus forms the front wall of the casing, curving and slanting forward and downward over the bar 1 at 54 and extending vertically therebelow at 55, whence the bottom side 56 of the channel slopes to the bottom edge of the head block 18 (Fig. 3) against which it may fit rather loosely. The track ballast 57 is packed against the lower parts of the casing, and no attempt is made to close either end thereof, either at the rail 34 or next to the housing 19; the object being to allow free drainage into and out of the casing as the best means of avoiding clogging around the bar 1, by dirt or freezing. Further to facilitate drainage, the bottom side 56 preferably is sloped from the track end outward as seen in Fig. 3; and as this side 56 also inclines to the head block or tie 18, the drainage will be along this inner corner, and partly down into the ballast 57 past the loosely fitting lower edge of the casing. At the same time, this lower side 56, abutting the tie 18, affords the required lower support for the front portions 54 and 55 if these receive the impact of a collision, which they tend to divert up over the top of the tie 18 away from the bar 1. If the colliding object catches under the bottom of the casing, to do which, however, it must tear away the ballast 57, it may tear up the casing; but in so doing, the casing, fixed at its top edge, tends to act as a lever swinging out forwardly and up, to fend the object away from the bar 1. The terminal casing 51 is similar to the longer section 50 in having a top over and screwed to the tie 18 by screws 58, and a front 59 sloping down and forward over the end part of the bar 1. Preferably its bottom is omitted, to permit better drainage away from the housing 19, and it has an outer closed end 60 and outer terminal flange 61 fastened to the lower part of the head block or tie 18 by the screw 62. It will be understood that this casing 51 will have its lower edges abutted by the ballast 57 also, although the ballast is not so deep at that place, sloping from the track, for drainage.

In the modification of Figs. 7, 8 and 9, it will be understood that the device will be located with relation to the switch-stand as is the device in Fig. 1, and the connection of the interlocking bar 1' to the rail will be similar; and this bar is guarded by the casing 50' (Fig. 4) with top 52', screws 53', front portions 54' and 55' and bottom 56' sloping as does the bottom 56 of the first example. Here, the bar 1' has its broader sides upright, and the front portions of the casing 50' vary accordingly from the corresponding parts in the preceding example; especially as the bar 1' is carried considerably nearer the top of the head block 18' than is the bar 1 of the first example. Also it will be understood that this bar 1' may have a suitable terminal guard or casing, not shown, just as with the bar of the example before described.

The different location of the bar 1' is in accordance with the different relation of the plunger that engages with it. Thus, the housing 19' comprises the top 20' from the front of which depends the stirrup-head 23' having the transverse rectangular open-

ing 24' through which the bar 1' slides in its movement with the switch point rail such as the rail 4. The head 23' has the bore 30' forward into the opening 24', with 5 a continuation 29' at the front side of the opening 24', not, however, continuing out through the front of the head, which is left 10 amply massive in front of the opening 24' to provide a strong cover for the front end 15 of the plunger 31' which slides in these bores 30' and 29' and, when the bar 1' registers its opening 33' with the bores, upon correct closure of the switch, slides through the bar as illustrated, in a horizontal direction instead of vertically as in the first example.

The housing top 20', which bridges the gain 22' in the head block 18', has, some distance from its rear end, the depending wall 20 member 63 fitting down across the gain and having a bore 64 alined with the bores 29' and 30', guiding the rear or head end part of the plunger 31', which has a collar 65 pinned on it and a helical spring 66 around 25 it between the collar 65 and the wall member 63, forcing the plunger 31' forward until the collar 65 engages the rear side of the head 23' as the plunger reaches its greatest forward extension through the 30 interlocking bar 1'. A rib 67 from the head 23' back to the wall member 63 on the lower side of the top 20' reinforces the top and head connection. A deeper rib 68 extends back from the wall member 63 on the lower 35 side of the top 20'; and the intermediate lever 69, which comprises side members joined by a neck 70 (Fig. 8) has the upper ends of its members straddling this rear rib 68, with the fulcrum pin 71 transversely through them and the rib. The lower ends of these intermediate lever members straddle the head or eye 32' of the plunger 31', with a pin 72 transversely through them and the eye. To the rear of and above the 40 neck 70, these members take the form of segments 42'. The locking ear 43' projects back from the rear end of the top 20' and rear rib 68, with a transverse opening 44' which is covered by the lever segments 42' as these swing up on backward swinging of 45 the lever 69 to withdraw the plunger 31' from the bar 1', preventing insertion of the padlock bow, which can be inserted in the opening 44' only if the plunger is safely 50 through the bar 1', upon which the bow, engaging the upper edges of the segments 42', prevents withdrawal of the plunger. Opposite the junctions of its side members with the neck 70, the intermediate lever 69 has laterally projected wings 72' (Fig. 9) and 55 a bottom plate 73 projects back from the bottom of the wall member 63, fitting in the bottom of the head block gain 22', and has on its rear end a hub 74 straddled by the 60 forked lower end of the treadle lever 75,

with a fulcrum pin 76 transversely through the fork members and hub. This treadle lever 75 also has a forwardly projected pair of fork members 77, straddling the intermediate lever 69 and engaging up against the wings 72' thereof, so that when this treadle lever is swung backward by pressure on the treadle 78 on its upper rear end it swings the intermediate lever backward, withdrawing the plunger 31' against the pressure of the spring 66, which returns the plunger into engagement upon release of the treadle and registry of the interlocking bar opening 33' with the housing openings 29' and 30'.
80

In this example, a rib 79 extends from the stirrup-head 23' down to the bottom of the front stirrup plate 80, from the bottom edge of which the housing bottom plate 81 preferably projects under the bottom of the tie or head block 18'. Four bolts 21' pass entirely through the bottom plate 81, head block 18', and housing top 20'; two bolts being at each side of the gain 22', which is suitably tapered for access and drainage, as in the gain 22 of the first example. This bolted-through connection affords an even stronger attachment of the housing to the head block than the distribution of screws 21 above and screws 26 below in the previous example; and is another illustration of the principle of fixing the housing not only to the top of the tie but to its bottom, as by the screws 26 in the other illustration. Also, it will be obvious that either kind of bottom attachment may be used with either kind of mechanism. The bolted-through connection is stronger; but requires considerable excavation under the tie to allow insertion of the bolts as illustrated, or application of the nuts, where they passed through from the top.
100

It will be noted that, in either example, there is no exposure of the plunger 31 or 31' at the front, or in an upper exterior part of the device; affording much greater security than is to be had in previous devices having the plunger end exposed at the front, which if struck might be forced back out of the bar; or, in those devices having a vertically moving plunger, its support is exposed above the head block, in danger of complete displacement. In the second example, the spring actuation of the plunger is more positive than the gravity actuation in the first example; but if the spring breaks, the second device lacks automatic return of the plunger to locking position, although, with the padlock in place, the plunger can be securely held engaged until a new spring is installed. Of course spring actuation is not confined to horizontal plunger movement; or gravity may be made to actuate a plunger horizontally; examples of either variation being found in the prior 125
130

art. But I have sought to illustrate two leading types of plunger operation embodied in my invention having the advantages of security lacking in any of the prior art examples. Also the prior art will show means other than treadles for applying power to the mechanism; but the examples as illustrated, both with treadles, sufficiently exemplify the advantages of my invention, to which the modifications of power application may be applied without departing from its scope. Similarly, other modifications may occur in practice, and therefore, while I have somewhat specifically illustrated and described preferred embodiments of my invention, I do not wish to be understood as being limited to such precise disclosure, but having thus fully described my invention, what I claim as new and desire to secure by Letters Patent is:

1. A switch interlocking device comprising positively engaging interlocking elements and operating means for one of said elements, said interlocking elements and said operating means being entirely below the level of the top of the switch head block.

2. A switch interlocking device comprising interlocking elements and operating means for one of said elements, said interlocking elements and said operating means being entirely below the level of the top of the switch head block, and the other one of said interlocking elements being alongside the head block, and means covering this other one of said elements.

3. A switch interlocking device comprising interlocking elements and operating means for one of said elements, said interlocking elements and said operating means being entirely below the level of the top of the switch head block, and means for locking said operating means below the level of the top of the head block.

4. A switch interlocking device comprising interlocking elements, operating means for one of said elements, and a housing for said operating means having its top extended along and fixed to the top of the switch head block, said interlocking elements and said operating means being entirely below the level of the top of the head block.

5. A switch interlocking mechanism comprising an interlocking bar and a plunger engaging said bar below the level of the top of the switch head block, and a lever connected to said plunger and having its fulcrum below the level of the top of the head block.

6. A switch interlocking device comprising an interlocking bar and mechanism with a part at one end to retenitively engage said bar, said mechanism extending along the track from said bar, and locking means for said mechanism at the opposite end of said mechanism.

7. A switch interlocking mechanism comprising an interlocking bar and a plunger engaging said bar at one side of the switch head block, and a lever connected to said plunger and having its fulcrum below the top of the head block, and having operating means near the opposite side of the head block.

8. A switch interlocking mechanism partly embedded in and partly along one side of the switch head block and comprising means for locking said mechanism below the level of the top of and near the opposite side of the head block.

9. A switch interlocking mechanism comprising an interlocking bar and a plunger engaging said bar below the top of the switch head block, and a housing for said bar and plunger having its top extended along and fixed to the top of said head block.

10. A switch interlocking mechanism comprising an interlocking bar and a plunger engaging said bar below the top of the switch head block, said head block having a gain admitting part of said mechanism and having the bottom of said gain sloping from said bar and plunger.

11. A switch interlocking mechanism comprising an interlocking bar and a plunger engaging said bar below the top of the switch head block, said head block having a gain admitting part of said mechanism and having said gain increasing in width from said bar and plunger, and a treadle on said mechanism in the wider part of said gain.

12. A switch interlocking mechanism comprising an interlocking bar and a plunger engaging said bar below the top of the switch head block, said head block having a gain admitting part of said mechanism, a treadle on said mechanism in said gain, and means for locking said mechanism in said gain, said treadle and said locking means lying below the top of said head block.

13. A switch interlocking mechanism comprising an interlocking bar and a plunger engaging said bar below the top of the switch head block, and a housing for said bar and plunger entirely surrounding said plunger laterally and having its top extended along and fixed to the top of said head block.

14. A switch interlocking mechanism comprising an interlocking bar and a plunger engaging said bar below the top of the switch head block, a housing for said bar and plunger entirely surrounding said plunger laterally and having its top extended along the top of said head block, and fastening means securing said housing top to said head block, said housing being higher than said fastening means adjacent to said bar and plunger.

15. A switch interlocking mechanism comprising an interlocking bar and a plunger engaging said bar below the top of the switch head block, a housing for said bar and plunger entirely surrounding said plunger laterally and having its top extended along the top of said head block, and fastening means securing said housing top to said head block, said housing comprising a head adjacent to said bar and plunger, outwardly convex and higher than said fastening means.

16. A switch interlocking mechanism comprising an interlocking bar and a plunger engaging said bar below the top of the switch head block, and a housing for said bar and plunger having its top extended along and fixed to the top of said head block and having an extension fixed to said head block near the bottom of said head block.

17. A switch interlocking device comprising an interlocking bar connected to a rail of the switch, means to retentively engage with said bar below the level of the top of the switch head block, and operating means for said retentively engaging means entirely below the level of the top of the head block.

18. A switch interlocking device comprising an interlocking bar connected to a rail of the switch, means operated to retentively engage with said bar below the level of the top of the switch head block, and means for applying a padlock to prevent operation of said retentively engaging means, entirely below the level of the top of the head block.

19. A switch interlocking device comprising an interlocking bar connected to a rail of the switch, extending along the switch head block below the top thereof, and a casing extending along said head block and overlapping said bar.

20. A switch interlocking device comprising an interlocking bar connected to a rail of the switch, extending along the switch head block below the top thereof and at one side thereof, and a casing of channel cross-section extending along said head block and overlapping said bar, said casing having one side of the channel fixed to the upper part of the head block, and having the edge of the other side of the channel presented toward said side of said head block near the bottom of said side.

21. A switch interlocking device comprising an interlocking bar connected to a rail of the switch, extending along the switch head block below the top thereof and at one side thereof, and a casing extending along said side of said head block around said

bar and having a bottom sloping from the switch rail outward.

22. A switch interlocking device comprising an interlocking bar connected to a rail 65 of the switch, extending along the switch head block below the top thereof and at one side thereof, and a casing extending along said head block around said bar and having a bottom sloping from the switch 70 rail outward and also sloping toward and loosely engaging with said side of the head block near the bottom of said side.

23. A housing for switch interlocking mechanism comprising a top to lie on the 75 top of the switch head block, and a stirrup at one end of said top to receive the interlocking bar of the mechanism.

24. A housing for switch interlocking mechanism comprising a top to lie on the 80 top of the switch head block, and an extension at one end of said top to receive the interlocking bar of the mechanism, said extension also having an opening under said top to admit a plunger to the bar, but 85 being closed on all sides out from under said top.

25. A housing for switch interlocking mechanism comprising a top to lie on the 90 top of the switch head block, and an extension at one end of the top to receive the interlocking bar and plunger of the mechanism, and having a downward extension to enter a gain in the head block for supporting part of the mechanism. 95

26. A switch interlocking mechanism to be mounted on the switch head block, comprising an interlocking bar and a plunger at one side of the head block, operating means for the plunger extending across the 100 head block, and means near the opposite side of the head block for applying a padlock to said operating means.

27. A switch interlocking device comprising interlocking elements and operating 105 means for one of said elements, said operating means extending through the switch head block from side to side thereof entirely below the level of the top thereof.

28. A switch interlocking device comprising interlocking elements and operating means for one of said elements, said interlocking elements having their interlocking engagement near one side of the switch head block and both of said elements and said operating means being entirely below the level of the top of the head block, and means near the opposite side of and below the level of the top of the head block for locking said operating means. 110 115

JOHN T. McGARRY.
